LATCH CONTROLLED COMPRESSOR

Clarence W. Straubel, Youngstown, Ohio, assignor to The General Fireproofing Company, Youngstown, Ohio, a corporation of Ohio

Original application October 18, 1941, Serial No. 415,611. Divided and this application July 9, 1943, Serial No. 494,064

2 Claims. (Cl. 129—26)

This invention is a division of my application, Serial No. 415,611, filed October 18, 1941, Patent No. 2,330,318, dated September 28, 1943, relating to filing cabinets and more particularly to an improvement in filing drawers.

One of the objects of the invention is to provide a drawer with a front compressor plate which, when the drawer is pulled open, may be manually moved from its inwardly tilted position to a forward position in which it may be locked to the drawer head, thereby to hold the compressor plate out of contact with the drawer contents while filing material therein and, on the other hand, may be automatically released as the drawer proceeds to a fully closed position.

A further object of the invention is to provide a compressor plate pivoted at its lower edge to the drawer body and having means at its upper portion for cooperating with a latch device carried by a drawer head which is slidably mounted relative to the drawer body.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawing, in which:

Fig. 1 is a fragmentary side elevation of a drawer with a telescopic drawer head including means for manually locking the compressor to the drawer head and effecting its automatic release as the drawer proceeds to a fully closed position.

Fig. 2 is a detail horizontal section taken on the line 2—2 of Fig. 1 showing the keeper on the compressor engaged with the latch.

Fig. 3 is a fragmentary elevation of the inner face of the drawer head of Fig. 1 showing the opening for receiving the keeper and the latch.

According to the arrangement shown in Fig. 1, the drawer head B' is provided with rearwardly directed drawer extensions B² which slidably and telescopically engage the drawer body A² so that the head B' is extensible relative to the drawer body.

The compressor C² is pivoted on the spring pintle or axis 1 carried by the brackets 2 secured to the bottom of the drawer body A² and, when the compressor is moved away from the drawer contents it may be caused to assume an unrestrained substantially upright position, as shown by the intermediate dotted line position (Fig. 1)

before the drawer head is pulled away from the drawer, or it may also assume the forwardly tilted restrained position shown by the dotted lines at the left (Fig. 1) when the drawer head B' is extended relative to the drawer body. In other words, when the drawer is pulled out of the cabinet by means of the handle 13 and the drawer head B' has been extended to any point within the maximum distance provided by the limiting stops 16 operating in slots 17, the compressor plate C² may be manually swung through a relatively wide arc so that the keeper arm 4b thereof engages with the edge of the latch 5b carried by the drawer head to hold the compressor plate at a forward inclination and thus provide a wide angle of support for the drawer contents when the drawer is open and filing procedure is being conducted.

As will be observed more especially from Fig. 3, the inside face of the drawer head B' is provided, near the upper edge thereof, with an opening or slot 18 which is preferably of vertically elongated formation. This opening provides access to the space between the front and rear plates of the drawer head and, as will be apparent from Fig. 2, this space contains a bracket 19 of substantially U-shaped formation which is preferably welded or otherwise secured to the inside face of the outer plate of the drawer head. The arms of said bracket 19 are provided with slots for respectively guiding the head and tail portions of the latch 5b, which, as will be apparent from Fig. 3, has its body made in substantially T-shaped formation so that the head provides a relatively elongated keeper engaging portion. The shank or tail portion of the latch body is surrounded by a spring 20 confined between the shoulder provided by the inner side of the head of the latch and one of the arms of the bracket. Thus the locking edge of the latch 5b is normally projected into the opening 18 by the force of the spring 20 and may be pushed backwardly against the compressive force of the spring. It will also be observed that the length of the edge of the latch 5b exposed within the opening 18 is less than the vertical length of the opening itself. The reason for making the keeper engaging edges of the latch shorter than the long dimension of the opening, or alternately making the long axis of the opening longer than the effective edge of the latch, is to provide a clearance space 21 which permits keeper 4b to become readily disengaged automatically from the latch when the drawer head B' is fully telescoped relative to the drawer body.

As will be apparent from Fig. 1, when the drawer head B' is fully closed relative to the drawer body, the compressor plate C² is not restrained and assumes the full and dotted line position inclined rearwardly of the drawer and the stops C' rest on the upper edges of the drawer sides. If the drawer becomes so crowded that the contents move the compressor plate C² from the full line position to the intermediate dotted line position shown in Fig. 1, it will be apparent that the keeper 4b will not engage with the latch 5b. However, when the drawer head B' is pulled outwardly relative to the drawer body, it will then be possible to manually move the compressor C² forwardly and engage the keeper 4b with the latch 5b at any point along the length of the edge of the latch depending on the distance that the drawer head is pulled away from the main drawer body. In other words, as the keeper 4b swings forwardly in an arc from its vertical position, it will engage the latch 5b.

Assuming that the drawer head B' is pulled outwardly relative to the drawer body and the keeper 4b is engaged with the latch 5b during filing procedure, and it is desired to close the drawer, the operator simply exerts pressure on the drawer head and pushes the drawer into the cabinet. And, when the drawer body reaches its inward limit of movement, the drawer head B' will then be telescoped or moved inwardly relative to the drawer body and thus the keeper 4b will slide upwardly along the edge of the latch 5b until it reaches the clearance 21' above the edge of the latch, whereupon the keeper becomes automatically disconnected from the drawer head and under the influence of its spring pintle the compressor moves toward drawer contents compressing position.

From the foregoing, it will be apparent that under all conditions when the drawer head B' is closed relative to the drawer body, the keeper 4b will be disengaged from the latch 5b. On the other hand, when the drawer head B' is extended, the compressor may be manually swung forwardly so that the keeper 4b becomes engaged with the latch to hold the compressor in the forwardly tilted position shown by dotted lines at the extreme left-hand part of Fig. 1. The

closing of the drawer will effect automatic release of the compressor, as above described.

I claim:

1. In a drawer for filing cabinets, a drawer body, a drawer head slidably movable with respect to the drawer body, said drawer head comprising inner and outer plates, the inner plate having an opening, a spring latch mounted between the inner and outer plates of the drawer head and having one edge thereof projected partially behind said opening, the vertical height of said latch being less than the vertical dimension of the opening to provide keeper escape clearance, a compressor plate pivotally supported on the drawer bottom adjacent to the inner side of the drawer head, and a keeper on the outer face of the compressor plate, said keeper being adapted, when the drawer head is moved outwardly relative to the drawer body, to engage the portion of the latch exposed behind the opening anywhere along its length, and when the drawer head is moved to a full inward position with respect to the drawer body, the said keeper escaping over the upper edge of the latch through the said clearance.

2. In a drawer for filing cabinets, the combination including a drawer body slidably mounted in the cabinet, a drawer head telescopically and slidably mounted at the front of the drawer body, a compressor plate pivoted to the drawer body adjacent the drawer head when the drawer is closed and manually swingable from an inwardly tilted drawer contents compressing position to an outwardly tilted drawer contents spreading position, a keeper on the outer face of the compressor plate having a horizontally disposed hook, and a latch on the inner face of the drawer head spring projected into the path of the hook of the keeper, said latch having a vertical keeper engaging edge for engaging the hook when the drawer head is extended, and said hook being slidable along said edge of the latch as the drawer head is moved and permit the compressor plate to swing to inwardly relative to the drawer until the hook moves off the top of the latch to release the hook drawer contents compressing position.

CLARENCE W. STRAUBEL.
